PAGE 2

Fig. 3

Fig. 4

Fig. 5.

Fig. 6.

Fig. 8.

Fig. 7.

FIGURE 1 is a perspective view of a lavatory, showing my new design;

FIGURE 2 is a side elevation thereof;

FIGURE 3 is a front elevation thereof;

FIGURE 4 is a plan view thereof;

FIGURE 5 is a perspective view of a lavatory showing another embodiment of my new design;

FIGURE 6 is a front elevation of FIGURE 5;

FIGURE 7 is a side elevation of FIGURE 5;

FIGURE 8 is a plan view of FIGURE 5.

Side views of the design not shown are substantially the same as the side views shown in FIGURES 2 and 6.

I claim:

The ornamental design for a lavatory, substantially as shown and described.
